UNITED STATES PATENT OFFICE

2,337,450

FREEZING TRAY

Ralph H. Chilton, Dayton, Ohio, assignor to General Motors Corporation, Detroit, Mich., a corporation of Delaware

Application February 27, 1937, Serial No. 128,153

12 Claims. (Cl. 62—108.5)

This invention relates to freezing containers, especially to portable freezing trays adapted for use in house-hold refrigerators.

An object of this invention is to provide improvements in such presently known devices whereby the frozen ice blocks may be removed without the necessity of melting the frozen bond between the tray parts and the ice. A more specific object is to provide improvements over the device disclosed in application S. N. 98,213, filed August 27, 1936, by Donald H. Reeves and assigned to the assignee of this application. One feature of such improvements is greater simplicity of structure and fewer parts whereby the cost of manufacture of this present device is very materially less but its efficiency in operation is maintained.

A feature of this invention is the elimination of any actuating hand levers or similar devices to cause relative movement between the grid parts to facilitate the removal of the frozen ice blocks. In this device relative movement between the grid parts is obtained by a simple blow, or other externally applied force, on one end of the assembled grid. Also in this device the required "head-room" between the water level and the highest point of the tray mechanism may be kept very small, and hence there will be less head-room required in the freezing compartment for a stack of the trays of this invention. In other words, nearly the full depth of the entire tray device may be utilized by filling with water to a relatively higher level.

Another feature is the simple method of loosely assembling the cross partitions to the longitudinal partition, whereby the desired relative movement between these parts is readily permitted. Also in the final assembled structure, the tilting movement of the cross partitions is permitted without the necessity of crushing out any such substantial necks of ice as would render its normal operation materially more difficult or to crack up the ice blocks.

Further objects and advantages of the present invention will be apparent from the following description, reference being had to the accompanying drawings wherein a preferred embodiment of the present invention is clearly shown.

In the drawings:

Fig. 1 is a plan view of a portable ice tray and grid made according to this invention.

Fig. 2 is a section on line 2—2 of Fig. 1.

Fig. 3 is a section on line 3—3 of Fig. 1.

Fig. 4 illustrates the actuation of the grid of Figs. 1, 2 and 3 to remove the frozen ice blocks

therefrom after the grid is removed from the pan.

Fig. 5 is similar to Fig. 4, except here the actuating member is being forced to the left whereas it is being forced to the right in Fig. 4.

Figs. 6 and 7 illustrate a method of assembling the one-piece cross partitions upon the two-section central wall. In Fig. 6 the upper section of the central wall is in final location while the lower section thereof (shown in dot-dash lines) is being passed endwise thru the slots in the cross partitions. Fig. 7 is a section on line 7—7 of Fig. 6.

Fig. 8 is a plan view of a second form of the invention wherein all the cross partitions lean against shoulders on the upper section of the central wall when in normal freezing position, and wherein said upper section is to be bumped in only one direction (toward the right).

Fig. 9 is a section on line 9—9 of Fig. 8.

Similar reference characters refer to similar parts throughout the several views.

The container pan 10 may be any known type of pan but is preferably a one-piece metal pan pressed from sheet aluminum and having some degree of flexibility as a whole. Preferably it is shaped according to the disclosure of the pan in S. N. 88,559, filed July 2, 1936, by Harvey D. Geyer and assigned to the assignee of this application, now Patent No. 2,122,937.

The grid of Figs. 1 to 7 is indicated as a whole by 11 and is made to be inserted freely into pan 10 either before or after pan 10 is filled to the desired level with water to be frozen. Grid 11 comprises a series of separate cross partitions 12 and a central main wall composed of an upper section 13 and a lower section 14, all of which are mutually relatively movable to a limited degree. The upper and lower sections 13 and 14 are held substantially aligned in a vertical plane by their sliding fit in the aligned slots 15 in the cross partitions 12.

In order to assemble the cross walls 12 upon the sections 13 and 14, each cross wall 12 has a central slot 15 cut or punched therein of a sufficient depth to permit the wider of the two sections 13 and 14 to be passed endwise thru said slots 15. In addition, each cross wall 12 has a metal flap 16 sheared at the two cuts 17 therein (see Fig. 3) and then bent out at such an angle as will temporarily provide a slot of sufficient width to permit the two sections 13 and 14 to lie side by side in said slot (see Figs. 6 and 7). The sections 13 and 14 may then be passed endwise in overlapping relation thru said slots in cross walls 12. When each cross wall 12 registers with

its notch 20 in the upper edge of section 13 and with its notch 21 in the lower edge of section 14, said sections 13 and 14 may then be moved vertically so as to cause them to no longer mutually overlap, whereupon they are moved laterally into the same vertical plane. The metal flaps 16 are then bent back into the planes of the cross walls 12, and thus sections 13 and 14 are held permanently in substantial alignment but mutually relatively slidably endwise in slots 15 in the cross walls 12.

The preferred shape of notches 20 and 21 are best shown in Fig. 2. The lower notches 21 are triangular except for the flat apex thereof against which the bottom of slot 15 is pressed in each case by the fact that the lower edge of each cross wall 12 bears upon the bottom of pan 10. This forces each cross wall up against the flat apex in its notch 21 and so tends to maintain each cross wall 12 in vertical position during freezing.

The upper notches 20 each has two opposed shoulders 22 and 23 on opposed sides of each cross wall 12 and having progressively widening clearances 25 and 26 therewith from one end of the grid to the other. For instance, in Fig. 2 the clearances 26 vary progressively from a maximum at the right end of the grid to a minimum at the left end of the grid, and clearances 25 vary from a minimum at the right end of the grid to a maximum at the left end of the grid. Hence when upper section 13 is moved longitudinally to the right, as shown in Fig. 4, the shoulders 22 engage cross walls 12 successively beginning at the right end of the grid and tilt said cross walls 12 forward one after the other. Conversely, when upper section 13 is moved to the left, as shown in Fig. 5, the shoulders 23 engage the cross walls 12 successively beginning at the left end of the grid and tilt said walls 12 forward one after the other in the opposite direction. Thus it is seen that the cross walls 12 will be tilted or moved successively one after the other entirely regardless of which direction the actuating upper section 13 is moved. An obvious advantage of this feature is that it permits section 13 to be moved alternately first in one direction and then in the other to materially facilitate the removal of the ice blocks with a minimum of applied force.

The upper section 13 is provided with a substantial quite rigid projection 30 at each end thereof, which preferably extends beyond the end lips of pan 10 and is then turned down and terminates at 31 at a point below any immediately adjacent portion of pan 10. The lateral width of portions 30 may be made as wide as desired to give a proper bearing area for bumping same against a table or any other solid body, or simply for applying pressure thereto against with the hands.

In operation, the grid is set snugly within pan 10 as shown in Fig. 2, filled with water to a level limited only by the top edge of pan 10, and set within a freezing chamber until the ice is solidly frozen and bonded to all contacting metal surfaces. To remove the frozen ice blocks, the pan 10 may be first removed by setting same on a table and pressing down on two diagonally opposite corners thereof to slightly flex said pan 10 to cause it to loosen from the ice and grid contents, or by any other suitable method. With the combination here disclosed the pan 10 may be removed from its contents by resting one end of the pan 10 on a table and propping the other

end up slightly with the end 31 of projection 30 resting on a solid object and then pressing down with the hands on the two high corners of pan 10. The resulting up force on the grid and down force on pan 10 will readily separate pan 10 from its frozen contents. The individual ice blocks may then be removed from the grid by a slight blow or other force on either end projection 30, as illustrated in Figs. 4 and 5. By limiting the force of the applied blow or pressure the number of ice blocks removed at one time may be limited according to desire.

If desired, the cross walls 12 may each be provided with an offset slotted flange 40 at its upper edge having a slot 41 therein within which the upper edge of section 13 slides (see left end of Fig. 2). By this means the cross walls 12 will each be positively retained at right angles to the plane of the central wall, but said flanges 40 will not interfere with the proper operation of the device as described above. When the cross walls 12 are tilted and drop down slightly by actuation of section 13, these flanges 40 simply take the position shown at the right side of Fig. 4. In other words flanges 40 do not prevent the desired tilting and dropping movements of the cross walls 12.

The form of the invention shown in Figs. 8 and 9 will now be described. In this form the cross walls 12' are preferably inclined from the vertical when in normal freezing position, and each has a slotted flange 40' having a slot 41' therein within which the upper edge of the upper section 13' slides. Now when the grid 11' is inserted into pan 10, the cross walls 12' will each be tilted over in the same direction until the bottom of its slot 41' rests against its shoulder 23 (see Figs. 8 and 9). This normal tilted position of cross walls 12' is caused both by the action of gravity and by the bottom edge of each cross wall 12' bearing upon the bottom of pan 10 and forcing said cross wall up against the top of the lower notch 21' at the bottom margin of the lower section 14'.

In operation of this form of the invention the ice is frozen solid in the tray while all parts of the grid are as shown in Figs. 8 and 9. To remove the frozen ice blocks the pan 10 may be removed by any method described hereinabove, after which an external force is applied to upper section 13', as shown by arrow A in Fig. 8, to cause successive tilting of the cross walls 12' in a manner very similar to that described above in connection with the form shown in Fig. 4. In other words, the shoulders 22' successively engage and tilt the cross walls 12' due to the progressively greater clearances from the right side of Fig. 9 to the left side of Fig. 9. After each cross wall 12' is tilted forward sufficiently to release the two ice blocks in front of same, it is then free to drop down a slight distance and can then be moved forward and further tilted sufficiently to permit the required further movement to the right (in Fig. 9) of the upper section 13' in order to complete the tilting actuation of cross walls 12'.

A further feature of the form shown in Figs. 8 and 9 is the extension of the strong rugged end projection 30' so that its lower end 31' lies below the plane of the bottom of pan 10. When this structure of grid is used with a slightly flexible metal pan 10, the pan may be readily removed from its frozen contents simply by setting the tray upon a flat table or other solid surface (indicated by line 50 in Fig. 9) and then pressing

down with the hands on the two high corners of pan 10. The illustrated clearance 51 between the pan bottom and surface 50 permits the resulting up force on the grid and down force on pan 10 to slightly flex pan 10 and readily separate it from its frozen contents by a sort of peeling action. The removal of the individual ice blocks from the grid may then be accomplished as above described. Preferably a plate 32 of substantial area is spot-welded or otherwise fixed to the front of projection 30' in order to stiffen same and at the same time provide a greater bearing area for the application of the external force A. For instance, with such a relatively large bearing area the above-described actuation of upper section 13' may be readily accomplished by bumping against plate 32 with the ball of the hand.

A still further feature of the form shown in Figs. 8 and 9 is the inclined cam surface 60 at the right end of the upper section 13' (as seen in Fig. 9) which is arranged to engage the end lip 61 of pan 10. Thus a further possible method of removing pan 10 from its frozen contents is simply to apply force A (that is, to bump the opposite end of section 13'). This will first slide the ice-embedded portion of section 13' thru its molded groove in the ice, thereby causing cam surface 60 to ride upon lip 61 of pan 10 and force same outwardly and downwardly and thus free pan 10 from its frozen bond to the ice block contained therein. The grid and ice is then removed from the pan and the separate ice blocks removed from the grid as above described.

In all herein disclosed forms of the invention, the longitudinal movement of the actuating upper section 13 or 13' may be greatly facilitated by first loosening its ice-embedded lower margin from the ice. This can readily be done, either before or after pan 10 has been removed from the ice contents, simply by grasping the entire unit with the hands and banging the end surface 31 or 31' of the depending projection 30 or 30' as the case may be against a solid surface such as a table. Obviously such banging will also often loosen pan 10 from its frozen contents although this method of loosening pan 10 is optional.

The upper longitudinal sections 13 and 13' are preferably made from relatively heavy smooth stainless steel in order to withstand the forces exerted thereupon during actuation of the device as above described. The pan 10, the cross partitions 12 and 12', and the lower sections 14 and 14' are preferably made of anodized sheet aluminum, and given a very thin coating of a suitable grease or a high melting point wax to facilitate the separation of the ice from the contacting metal surfaces.

While the embodiment of the present invention as herein disclosed, constitutes a preferred form, it is to be understood that other forms might be adopted, all coming within the scope of the claims which follow.

What is claimed is as follows:

1. A partitioning grid for a freezing tray, said grid comprising: a main wall having relatively longitudinally movable upper and lower sections, and a series of transverse partition walls each loosely retained upon said main wall and being capable of a tilting movement relative thereto; said upper section of said main wall having means thereon serving to successively engage and tilt said transverse walls upon longitudinal movement of said upper section relative to said lower section.
2. A partitioning grid for a freezing tray, said grid comprising: a main wall having relatively longitudinally movable upper and lower sections, and a series of transverse partition walls each loosely retained upon said main wall and being capable of a tilting movement relative thereto; said upper section having a series of shoulders adjacent its upper edge which upon longitudinal movement of said upper section successively engage and tilt said transverse walls to facilitate the ejection of the frozen ice blocks.
3. A partitioning grid for a freezing tray, said grid comprising: a main wall having relatively longitudinally movable upper and lower sections, and a series of transverse partition walls each loosely retained upon said main wall and being capable of a tilting movement relative thereto; said upper section having a series of shoulders adjacent its upper edge which upon longitudinal movement of said upper section successively engage and tilt said transverse walls to facilitate the ejection of the frozen ice blocks, said upper section having an end projection adapted to receive a sudden blow to cause it to move longitudinally relative to said lower section.
4. A partitioning grid for a freezing tray, said grid comprising: a main wall having relatively longitudinally movable upper and lower sections, and a series of transverse partition walls each loosely retained upon said main wall and being capable of a tilting movement relative thereto, said upper section of said main wall having means thereon serving to successively engage and tilt said transverse walls upon longitudinal movement of said upper section relative to said lower section, said upper section having a projection extending beyond the frozen ice blocks and adapted to receive an externally applied blow to cause it to move and tilt said transverse walls.
5. The combination of a freezing tray and a removable grid disposed therein, said grid comprising a longitudinal partition formed of a plurality of elongated sections one superposed upon and slidable upon another, and a series of partition elements carried by and extending transversely of said elongated partition to provide therewith and with said tray a series of ice cube compartments, said elongated section being constructed to provide an end wall for each cube compartment having a smooth face extending from the top to the bottom of such compartment, said transverse elements being so mounted as to be tilted by relative movement of said elongated sections and thereby break the bond between the grid and the ice cubes frozen therein after the grid structure has been removed from the tray.
6. A device of the character described comprising a tray, a grid assembly removably positioned in the tray comprising a notched member extending longitudinally of the tray, a plurality of wall members extending transversely of said longitudinal member and loosely held in spaced relation in the notches of said longitudinal member, said transverse members being normally inclined with respect to the bottom of the tray and adapted for angular movement from normal position, and mechanism carried by the grid assembly adapted to contact the tray to first raise the grid assembly relative to the tray and then move the transverse members from their normal inclined position.
7. In liquid congealing apparatus, the combination of an ice pan, a grid member removably disposed therein for dividing the ice pan into a plurality of ice cube forming cells, said grid mem-

ber comprising a central longitudinal wall member formed of two superposed parts both of which divide the ice pan longitudinally thereof and one of which is movable lengthwise relative to the other, and a plurality of transverse wall members movably attached to said longitudinal wall member, each of said transverse wall members being provided with a slot in the center thereof to receive both of said longitudinal wall sections, said top longitudinal wall member being provided with a series of slots in the top thereof and said bottom longitudinal wall member being provided with a series of slots in the bottom thereof, said slots in said longitudinal wall members receiving said transverse wall members and being of sufficient width to permit angular movement of the transverse wall members relative to the longitudinal wall members when the transverse wall members are rotated by movement of one of the longitudinal wall members relative to the other, after the grid member has been at least partially removed from the ice pan.

8. The combination of an ice tray embodying side and bottom walls and a grid removably disposed therein and arranged to cooperate therewith for forming ice cubes, said grid comprising a longitudinal member composed of a plurality of relatively movable longitudinal extending sections disposed substantially in the same vertical plane, and a series of spaced substantially rigid transverse fins extending across the width of the ice tray, said grid being open at its bottom so that the ice cubes contact the bottom of the tray; said fins extending into slots on said longitudinal member and being loose with respect to the sections of the longitudinal member and arranged to have movement in relation to said longitudinal sections and means associated with said longitudinal member for imparting such movement to the fins.

9. A partitioning grid for a freezing tray, said grid comprising: a composite partition wall having relatively longitudinally movable upper and lower sections, a series of transverse partition walls each extending transversely to and associated with said composite wall in such manner as to permit each of said transverse walls to move relative to both of said upper and lower sections, said composite wall having means for engaging and moving said transverse walls upon relative longitudinal movement between said upper and

lower sections thereof to facilitate the loosening of the frozen ice contents from the grid.

10. A removable partitioning grid for forming ice block compartments in a freezing tray, said grid comprising: a longitudinal partition wall having a substantially rigid actuating member extending longitudinally along its length and slidably relative thereto, a series of transverse partition walls each loosely retained upon and movable relative to said longitudinal partition wall, said transverse walls being moved relative to each other and to said longitudinal wall by the longitudinal movement of said actuating member, said actuating member having a projecting end portion extending endwise beyond the frozen contents of the grid and arranged to receive the full endwise impact when the grid with its frozen contents is bumped endwise against an outside body so as to move said actuating member longitudinally.

11. A removable partitioning grid for forming ice block compartments in a freezing tray, said grid comprising: a main longitudinal partition wall, a series of transverse partition walls spaced apart along the length of said main wall, said transverse walls each being tiltable to facilitate the removal of the frozen contents of the grid, said main wall having associated therewith a relatively longitudinally movable actuating member extending along the length of said main wall and having means for engaging and tilting said transverse walls, said actuating member having an impact-receiving portion extending endwise beyond the frozen contents of the grid and so arranged as to receive the endwise impact when the grid with its frozen contents is bumped endwise against an outside body so as to move said actuating member longitudinally.

12. A freezing tray and a removable grid therefor, said grid having a longitudinal wall and a series of cross walls movable relative thereto, said longitudinal wall having a longitudinally extending actuating member for moving said cross walls relative to said longitudinal wall, said actuating member having an impact-receiving portion extending endwise beyond all other parts of the grid or tray when in freezing relationship and so arranged as to be moved longitudinally by the endwise impact when the tray assembly with its frozen contents therein is bumped endwise against an outside body.

RALPH H. CHILTON.
